United States Patent

Des. 237,579
Patented Nov. 11, 1975

237,579

FORK OR SIMILAR ARTICLE

Gunnar Cyren, Gayle, Sweden, assignor to Dansk International Designs Ltd., Mount Kisco, N.Y.

Filed July 3, 1974, Ser. No. 485,650

Term of patent 14 years

Int. Cl. D7—03

U.S. Cl. D7—137

FIG. 1

FIG. 2

FIG. 3

FIG. 4

FIG. 5

FIG. 1 is a top plan view of a fork or similar article embodying my novel design;

FIG. 2 is a side elevational view thereof;

FIG. 3 is a bottom plan view thereof;

FIG. 4 is a front end elevational view thereof; and

FIG. 5 is a rear end elevational view thereof.

I claim:

The ornamental design for a fork or similar article, as shown.
